UNITED STATES PATENT OFFICE.

R. P. WILLIAMS AND EPHRAIM B. MORRELL, OF SANTA CRUZ, CALIFORNIA.

WELL-BORING DRILL OR BIT.

SPECIFICATION forming part of Letters Patent No. 321,560, dated July 7, 1885.

Application filed March 1, 1884. Renewed January 6, 1885. (No model.)

To all whom it may concern:

Be it known that we, R. P. WILLIAMS and EPHRAIM B. MORRELL, citizens of the United States, residing at Santa Cruz, in the county 5 of Santa Cruz and State of California, have invented a new and useful Well-Boring Drill or Bit, of which the following is a specification.

Our invention relates to improvements in 10 drills or bits for boring or sinking wells; and the object of my improvement is to provide a drill or bit which may drill a hole in advance of the casing being sunk, and of a diameter greater than that of the casing, and yet so constructed and arranged that it may be readily 15 forced down and drawn back through the casing when its cutting-edge becomes dulled. These objects we accomplish by means of the device illustrated in the accompanying drawings, in which—

Figure 1 is a side elevation of our improved drill with the sliding or movable bit drawn out. Fig. 2 is a view of the same when closed up and ready for work. Fig. 3 is an elevation of the drill, showing the tripping-disk removed. Fig. 4 is an edge view of the lower part of the drill, showing the removable cutting-edge. Fig. 5 is a section taken on line X-X of Fig. 3. Fig. 6 is a section taken on line 25 Y-Y of Fig. 3. Fig. 7 is a horizontal section taken through one of the slush-holes.

Similar letters of reference are used to indicate like parts throughout the several views.

A represents the main or fixed portion of 35 our improved drill or bit, and B the movable or sliding portion of the drill, provided upon its inner face with a dovetail tenon, C, which engages with a mortise, D, in the meeting edge of the main bit, and thus lateral motion 40 is prevented when the movable part of the bit is shoved home. The upper part of the movable drill rests against an under-cut jog or rabbet, E, cut in the edge of the fixed drill, and about one-half way down the meeting edge thereof we cut a second but shorter rabbet, F, and provide the movable bit with a corresponding projection, G, which fits up snugly against the rabbets both at this point and at the upper rabbet, E, and thus a support is formed to take up and receive the upward thrust of the movable bit, and the lower or cutting edge of the two sections of the drill

are kept constantly aligned when drilling. Slush-holes H H, extending through the body of the drill from side to side, are placed at the 55 upper inner angles of the rabbets in the main bit-stock to permit of the outward passage of the sediment and slush when the two parts of the drill are forced together at the bottom of the well hole or shaft. 60

At any convenient point on the main section of the drill between the upper and lower rabbet we make a transverse slot, I, cut in one face only of the drill, as shown in Fig. 5. This slot is fitted with a dovetailed sliding catch or 65 pin, J, which is forced outwardly by a coiled spring, K, placed within the slot, and the said pin is prevented from passing out of the slot by a pin, L, which strikes against a shoulder formed in the slot. A thin flat loosely- 70 pivoted disk, M, is attached to the sliding spring-catch, and the outer edge of this disk is projected sufficiently far beyond the edge of the drill (see Fig. 2,) to strike against the lower edge of the well-casing when the drill is 75 to be withdrawn from the well-hole, and, by forcing back the spring-catch J, release it from a vertical rabbet or mortise, N, cut in the meeting face or edge of the movable bit B, and allow the bit to drop down far enough to permit the outer lower corner of the cutting-face 80 to clear the lower edge of the casing and permit the drill to be drawn up to the surface of the ground. The rabbet N is made long enough to permit of the movable bit dropping 85 far enough to clear the casing, and at the lower end of this rabbet a pin, O, is projected from the main bit, and as the movable bit drops its fall is limited by the upper end or shoulder of the rabbet N coming in contact and resting upon 90 the said pin O. It should here be remarked that the dovetailed tenon and mortise C D are not made vertical, but at a certain degree of inclination from a vertical line to enable the lower end of the movable bit to clear the casing after it has been dropped a certain 95 distance. This inclination should be such that the width of the drill upon the cutting-edge is seven inches, and at the upper end of the movable bit is six inches, and the 100 drop is three inches, then the angle should be such as will permit the lower outer corner of the movable bit to come within a vertical line dropped from that point on the outer edge of

the drill where the width is a fixed six inches. The cutting-edge of the drill is made removable, and in practice we drill a longitudinal hole in the lower edge of the stock in the form 5 shown in Fig. 4, and then insert the tempered-steel cutter *a*, having slight shoulders *b*, extending its entire length and confine the cutter in place by short screws *c*.

Having thus described our invention, what 10 we claim, and desire to secure by Letters Patent, is—

1. A well-boring drill or bit having a movable section, *B*, sliding up a vertically-inclined dovetail and mortise, and held in position by 15 a spring-catch operated by a disk to cause the movable section or bit to drop, substantially as shown, for the purpose set forth.

2. A well-boring drill having a movable section and connected together by a dovetail, *C*, 20 and mortise *D*, and provided with shoulders or rabbets *E* and *F*, and slush-holes *H*, substantially as shown, for the purpose set forth.

3. In a well-boring drill, the movable section or bit *B*, provided with a vertical rabbet,

N, adapted to receive the holding-pin *L*, projecting from the fixed section or bit *A*, substantially as shown, for the purpose set forth. 25

4. In a well-boring drill having a movable bit, the spring-catch *J*, countersunk in the main bit or section *A*, and engaging with a 30 rabbet, *N*, cut in the meeting face of the movable bit and operated by a disk, *M*, to allow the said movable bit to drop when brought into contact with and forced back by the lower edge of the well-casing, substantially as shown 35 and set forth, for the purpose specified.

5. In a well-boring drill, the cutters *a a*, secured within the lower face of the drill-stock and confined to place by shoulders *b* and screws *c*, substantially as shown, for the purpose set 40 forth.

In testimony that we claim the foregoing we have hereunto set our hands and seals.

R. P. WILLIAMS. [L. S.]
